UNITED STATES PATENT OFFICE.

WILHELM ULRICH ARBENZ, OF GLEIWITZ, AND OTTO KAMMERER, OF CHARLOTTENBURG, GERMANY.

RAIL-TRACK-SLUING MACHINE.

1,100,006.

Specification of Letters Patent. Patented June 16, 1914.

Application filed April 9, 1914. Serial No. 830,753.

To all whom it may concern:

Be it known that we, WILHELM ULRICH ARBENZ, mining engineer, residing at No. 5 the Promenade, Gleiwitz, in the Kingdom of 5 Prussia, Germany, and OTTO KAMMERER, engineer, residing at Charlottenburg, Berlin, Germany, subjects of the King of Prussia, have invented certain new and useful 10 Improvements in Rail-Track-Sluing Machines; and we do hereby declare the following to be a full, clear, and exact description of the invention, such as will enable others skilled in the art to which it appertains to 15 make and use the same, reference being had to the accompanying drawings, and to letters or figures of reference marked thereon, which form a part of this specification.

Our invention relates to machines for 20 sluing rail-tracks and more especially to machines of the kind that lift the rails and shift them laterally by means of rollers which are attached to the middle of a bridge that is supported at its ends upon two bogie 25 carriages.

The object of our invention is to produce 30 a highly effective rail-track sluing machine which is capable of shifting the track rapidly, uniformly and with precision while subjecting the rails to the least possible strain, which is simple in operation and 35 easily made ready for action and which can be applied equally well to various kinds of rail-track systems.

According to our invention the bridge of 40 the rail-sluing machine for lifting and sluing the rails is provided with sets of lifting and sluing rollers, which laterally embrace the two rails on which the carriages that support the bridge travel. The rollers 45 are arranged so that several of them are placed at each side of each of the two rails and that all of them are pressed against the rails simultaneously. They are also arranged so as to be removed from the rails 50 simultaneously and are mounted on vertical or approximately vertical axes. We provide these rollers with flanges at their bottom ends by means of which the rollers grip the rails beneath their top flanges when they are moved against the rails. The fish plates by 55 which the rails of the rail track are joined are planed or thinned down at their upper edges so that they still afford sufficient sup-

port to the upper flanges of the rails but are not struck by the rollers that grip the rails. 55

We attach the rollers on each side of each rail to a common block or support and we arrange all the blocks or supports so that they may be shifted in the proper manner by the turning of a spindle or other suitable 60 means, the ends of the supports that carry the rollers being moved toward the rails when the spindle is turned in the one direction and being moved away from the rails when the spindle is turned in the other 65 direction.

We mount the blocks with the shifting device on a slider which may be moved transversely across the bridge or in other words transversely to the rail-track. If the shifting or sluing operation is commenced after the sets of rollers have gripped the rails the rail-track will also be caused to shift. Further means are provided by which the slider with the rollers, and if desired also the rails 70 embraced by the rollers, may be raised. We also provide means for removing the machine at certain times from the rail-track on which it ordinarily travels, and which it is used to shift, and for putting it aside so that 75 other machines and devices that must be permitted to travel over the same track can be moved past the sluing machine. For this purpose we provide auxiliary tracks which can be fixed transversely to the ordinary 80 track and arrange lifting devices on the machine by which it can be transferred to the auxiliary track. We provide further means on our machine by which it may suitably shift a neighboring rail-track lying on 85 sleepers located near the track on which the machine ordinarily travels. 90

Other details and advantages of our invention will be elucidated in the following description in which reference is had to the 95 accompanying drawings.

Like parts in the various drawings are designated by similar reference characters.

Figure 1 represents a side view of an example of construction of our invention in 100 which the left end is shown in the position assumed when the machine is ready for executing a rail-shifting operation, while the right end is shown in the position assumed when the machine is to be removed from the 105 track. Fig. 2 is a cross sectional view on

the line A, B in Fig. 1. Fig. 3 is a plan view of the arrangement shown in Fig. 1 in which the machine travels on the two rails of a five-rail excavator track. Fig. 4 represents a view similar to that in Fig. 1 but in which different means are shown for moving the machine aside and Fig. 5 shows a cross section on the line C, D of Fig. 4 which corresponds to Fig. 2 and which explains the manner in which the machine travels on an auxiliary track. Fig. 6 shows an arrangement of a rotary auxiliary rail-track on a larger scale. Fig. 7 is a section on the line E, F of Fig. 6 and shows a stop for limiting the rotary movement of the auxiliary rail. Fig. 8 represents on a larger scale a side view of the lifting and sluing device that is arranged in the middle of the bridge, the device being shown in this figure in its operating position. Fig. 9 is a central vertical section of the machine on the line G, H of Fig. 8 or on the line J, K of Fig. 11, after a removable auxiliary device for shifting a second rail-track mounted on independent sleepers has been removed. Fig. 10 is a similar sectional view in which the machine is shown with the auxiliary device. Fig. 11 is a section on the line L, M in Fig. 10. Fig. 12 is a diagrammatic representation of the manner of shifting the rail-track in cases where there is an aggregation of cross sleepers which are common to all the rails that are to be shifted. Fig. 13 is a corresponding representation for cases in which there are two independent aggregations of sleepers. Fig. 14 shows on a still larger scale the form of the fish plates by which the sections of rails are joined to each other and from this figure may be seen the manner in which the rollers embrace the top flanges of the rails. Fig. 15 is a front view and Fig. 16 a side view of the auxiliary device for shifting a neighboring track.

On two bogies 1, 1 a bridge 2 is mounted from the middle of which sluing rollers 3 suspend. The sluing rollers 3 revolve on vertical axes and are provided at their lower ends with flanges 4. The fish plates 5 by which join the rails 6 with which the rollers 3 engage are planed down at their upper outer edges at 7 (see Fig. 14) so that the rail flange 8 is sufficiently supported by the fish plates 5 but that the flanges 4 of the rollers 3 are still enabled to grip the upper flange 8 of the rail with their whole breadth.

On each side of each of the two rails three rollers 3 are provided so that there are twelve rollers 3 in all. The axes of all of the rollers 3 at each side of each rail are fixed in a block 9 which has a pivot 10 at each end. The pivots 10 of all of the four blocks 9 are journaled in a transverse slider 11 that can be moved in the frame 13 on rollers 12.

The frame 13 cannot be moved transversely or longitudinally in the bridge 2 but it is arranged to be moved upwardly in the bridge. To this end the frame 13 is suspended from the bridge 2 by two screw spindles 14. Keyed to the upper ends of the screw spindles 14 are bevel wheels 15 which with bevel wheels 17 are mounted on a common shaft 16. A crank handle (not shown) may be slipped on to the four cornered end 17 of the shaft 16 and the shaft thus turned in either direction by hand thereby uniformly raising or lowering the frame 13 and all the rollers 3. If the rollers 3 are in engagement with the rails 6, as shown in Figs. 8, 9, 10 and 14, the turning of the shaft 16 would result in the whole rail-track at the middle of the bridge 2 being raised or lowered. Mounted in the middle of the transversely movable support or slider 11 is a block 19. A screw spindle 20 that is journaled in fixed bearings in the frame 13 is passed through and screwed at 21 into the block 19. If the spindle 16 is turned in one direction or the other by a crank the slider 11 and all the rollers 3 carried by it will be moved toward the left or right. If the rollers 3, as shown in Figs. 8-10 and 14, are in engagement with the rails 6 the whole rail-track is curved to the left or to the right as shown in Fig. 3.

For bringing the various rollers 3 simultaneously into and out of engagement with the rails the following device is provided:—Each of the four blocks 9 carries two vertical upwardly directed forked arms 22. These forked ends embrace the pivots 10 of the nuts 24. The nut 24 at the one side of each rail 6 is provided with a left hand thread and nut 24 at the other side with a right hand thread. All the nuts 24 are mounted on a common spindle 25 having corresponding left and right hand threads and this spindle is journaled in the middle block 19 of the transversely movable support 11 so as to be rotatable but not movable in any other direction. If the spindle 25 is turned by means of a crank 26 (Figs. 1 and 4) in the one direction or the other all the rollers 3 will be simultaneously swung outwardly or inwardly on the pivots 10 of the blocks 9 and will be thus brought into or out of engagement with the rails.

The simultaneous raising or lowering movements and the simultaneous lateral movements to one side or the other, and also the simultaneous inward or outward swinging movements of the various pairs of rollers 3 are effected by means of spindles 16, 20 and 25 respectively that are turned by cranks. As all the three movements, the vertical movement, the horizontal movement and the swinging movements are exe-

cuted by means of self-locking screw spin-
dles special locking devices for securing the
various adjustments are unnecessary and
the rollers 3 are capable of directly exerting
5 the very considerable forces that are re-
quired for bending the rail track laterally
and upwardly and for lifting the rails in
spite of the fact that they are easily mov-
able.

10 The rails 6 on which the bogie carriages 1
of the bridge 2 travel are not only intended
for the rail-track sluing machine but also
for other devices for example for transport
trucks. It is therefore desirable to be able
15 to remove the sluing machine from its track
at certain times.

In our rail-track sluing system we provide
auxiliary rails 27 for this purpose which
may be turned about the pivot 28, Fig. 6.
20 These rails are placed higher than the track
which has to be shifted, but the pivots 28
are mounted in a bearing that is fixed to the
sleepers 30 which support the rail-track that
is to be shifted. The rails 27 may be turned
25 so as to be parallel to the rails 6 (see Fig.
3 at the left) and they are generally kept in
this position. But they may be turned on
the pivots 28 so as to lie vertically with
respect to the main rails (see Fig. 3 at the
30 right). The rails 27 may be suitably sup-
ported in this position by blocks such as
31, Fig. 7. A stop 32 may be provided for
limiting the angle through which the rail is
turned. Means (not shown) may also be
35 provided for holding the rails in each of their
extreme positions. At the ends of the bridge 2
we provide means by which the bogies 1 may
be lifted from the rails 6 and the machine
transferred to the auxiliary rails.

40 In the case of the example of our invention
shown in Figs. 1-3 we provide sup-
porting blocks 33 at both ends of the bridge
2 next to the bogies 1 and above both of the
rail-tracks. These blocks 33 can be shifted
45 vertically in guides 34 with the aid of screw
spindles 35. In the example shown it is
assumed that each spindle is turned sepa-
rately by a crank (not shown) that is
slipped onto the four cornered end of the
50 spindle 35. A common driving means may,
however, be provided for each pair of spin-
dles 35 at either end of the bridge as in
the case of the spindles 14, Figs. 9 and 10.

Two pairs of transverse rails 27 are pro-
55 vided in the case illustrated for shifting the
rail-sluing machines in a transverse direc-
tion. When the auxiliary rails are in their
out-of-action position (see left side of Fig.
3) the one rail forms an extension of the
60 other and runs parallel to the excavator
track. When ready for action both trans-
verse rails 27 run parallel to each other and
vertically to the excavator track, so that
they themselves form a rail-track the gage

of which corresponds to that of wheels 36 of 65
the bogie 1. The distance between the two
transverse rail-tracks formed by swinging
around the pairs of auxiliary rails is exactly
equal to the distance between the pivots by
which the bridge 2 is attached to the bogies 70
1. The pivots 37 of the bogies 1 are so ar-
ranged that when the bridge is lifted the
whole bogie is raised with it.

If the rail-sluing machine is to be put
aside it is first moved to the position in 75
which the pivots 37 of the bogies 1 regis-
ter with the center lines of the transverse
tracks that would be formed by swinging
the rails 27, 27 around into their operative
positions. The auxiliary rails are then 80
turned into the positions indicated at the
left side of Fig. 3 by broken lines. The
supporting blocks 33 are then lowered by
means of the spindles 35 onto the rails 6, 6 of
the track and the bridge 2 together with 85
the bogies 1 is raised sufficiently to permit
of the bogies 1 being turned through an
angle of 90° and to allow of the auxiliary
rails being turned into their operative posi-
tions beneath the wheels 36 of the bogie 1. 90
The transverse rails are then fixed. If the
supporting blocks 33 are now screwed up-
ward and the bogies thus lowered to the
transverse tracks, the sluing machine may
now be moved aside on the transverse track. 95

The lifting of the bridge, the moving of
the transverse track into its operative posi-
tion and the lowering of the bridge onto
the transverse rails need not be carried out
at both ends simultaneously as assumed in 100
Figs. 1 and 2, but can be executed at one
end at a time.

In the example shown in Figs. 4 and 5 the
moving aside of the machine is not done
on the wheels of the bogies but upon special 105
wheels 38 which can be moved vertically in
guides 40 by means of spindles 39. With
this arrangement it is not necessary to re-
volve the bogies 1 and only two single
transverse rails 27 instead of two pairs of 110
transverse rails are required. When the
two transverse rails are in their operative
positions they form a transverse track the
gage of which is equal to the distance be-
tween the wheels or traveling rollers 38. 115

The device as described above will be
advantageously applied wherever all the
rails of the rail-track that is to be slued or
shifted are fixed to the same sleepers as
illustrated for example in Fig. 3. But in 120
many cases the rails are fixed to two differ-
ent sets or aggregations of sleepers. For
example, it often happens that three rails
are provided for an excavator and are fixed
to a common set of sleepers, while two 125
other rails that form a track for transport
trucks or the like are fixed to another neigh-
boring set of sleepers. By our invention

means are provided for sluing two rail-tracks which are adjacent to but independent of each other.

According to our invention an auxiliary device is provided which can be easily attached to or removed from the bridge 2 or the frame 11. Figs. 10 and 11 show the auxiliary device in its operative position. It has two pairs of sets of rollers 41 which are similar in shape to the rollers 3. The rollers 41 are mounted on blocks 42 that may be swung on pivots 43, which in turn are journaled in a frame 44. The blocks 42 have arms 45 the forked ends of which 15 embrace the pivots 46 of nuts 47 that are moved by a spindle 48 having right and left hand threads similarly as the nuts 24 are moved by the spindle 25. When the spindle 48 is turned in the one direction the rollers 20 41 are moved simultaneously toward a rail 49 and when the spindle is turned in the other direction the rollers are moved away from the rail.

The frame 44 is joined by a shaft 50 to 25 supporting pieces 51 which hold the nuts 52. These nuts may be turned on the spindles 53 the ends of which are fixed to the frame 11 by strong bolts 54. If the frame 11 is moved aside by means of the 30 spindle 20 it moves the frame 44 along with it causing it to execute the same amount of movement as itself. The nuts 52 are provided with worm wheels 55 that gear with the worms 56 which are mounted 35 on a common shaft 57. By turning the shaft 57 in the one direction or the other the wheels 55 and nuts 52 are actuated simultaneously and this causes the frame 44 and all its parts, especially the parts 41 to 40 approach or recede from the slider 11. By this means our machine can be adapted to various distances between the neighboring tracks and the machine.

The frame 44 is suspended on pivots 58 45 of a cross piece 59 in which a spindle 60 is journaled so as to be rotatable by a worm 61 and a worm wheel 62. At the upper end of the spindle there is a thread 63. This is screwed into a nut 64, which is held in 50 the frame of the bridge by pivots 55. If the spindle 60 is turned the thread in the nut is screwed up or down and by this means the frame 44 with the rollers 41 and the rails that might be embraced by the rollers are 55 raised or lowered.

The manner of operation of our device is as follows:—The machine is placed upon the rail-track that is to be slued and the rollers are lowered and caused to embrace the upper 60 flanges of the rails. The rollers are then raised and shifted transversely as much as it is desired to slue the track. The whole machine is then hauled over the track by a locomotive. While traveling the middle of

the bridge keeps continually moving the 65 rail-track with the sleepers out of the position indicated by unbroken lines in Fig. 12 into the position shown by broken lines and in moving farther along it lets the rails drop down to the ground. The first bogie 70 1 in the direction of travel will always travel on an unshifted section of track while the second bogie will travel on a shifted section. The position of the bridge will therefore be slightly oblique with respect to the direction of the rail track as seen in Fig. 3.

The operation of our machine in shifting two rail-tracks will be readily understood from the above explanations and by inspection of Fig. 13. The auxiliary device lifts 80 sleepers at the one side only while the other end is slid along the ground.

We claim:

1. In a machine for sluing rail-tracks having a plurality of rails, a bridge, two bogie carriages one at each end of the bridge, wheels supporting the said bogie carriages and adapted to travel on certain of the said rails, roller axes pointing in a downward direction, a set of rollers mounted on said axes at each side of each of the said certain rails, means for moving the sets of rollers at either side of each rail toward and away from the said rail, a flange at the bottom end of each roller adapted to embrace the rails when the rollers are moved up against the rails, a transversely movable support supporting said roller axes, means for moving the support transversely with respect to said bridge, a frame suspended from the bridge and holding the support and means for raising and lowering the said frame.

2. In a machine for sluing rail-tracks having a plurality of rails, a bridge, two bogie carriages one at each end of the bridge, 105 wheels supporting the said bogie carriages and adapted to travel on certain of the said rails, a block at each side of each of the said certain rails, a set of roller axes attached to each block and pointing in a downward direction, a roller on each axis, pivots at the ends of said blocks, the blocks being arranged to swing on said pivots, nuts attached to said blocks, a screw spindle with right and left hand threads screwed into 110 said nuts, means for turning the said spindle so as to move the sets of rollers toward and away from the said rails, a flange at the bottom end of each roller adapted to embrace the rails when the rollers are moved up against the rails, a transversely movable support supporting the said blocks, means for moving the support transversely with respect to said bridge, a frame suspended from the bridge and holding the support, 115 and means for raising and lowering the said frame.

3. In a machine for sluing rail-tracks

- having a plurality of rails, a bridge, two bogie carriages one at each end of the bridge, wheels supporting the said bogie carriages and adapted to travel on certain of the said 5 rails, a block at each side of each of the said certain rails, a set of roller axes attached to each block and pointing in a downward direction, a roller on each axis, pivots at the ends of said blocks, the blocks being 10 arranged to swing on said pivots, nuts attached to said blocks, a screw spindle with right and left hand threads screwed into said nuts, means for turning the said spindle so as to move the sets of rollers toward 15 and away from the said rails, a flange at the bottom end of each roller adapted to embrace the rails when the rollers are moved up against the rails, a transversely movable support supporting the said blocks, 20 a frame suspended from the bridge, a screw spindle journaled in said frame, and threaded in the said support into which the spindle is screwed, means for turning said spindle so as to shift said support in the frame, vertical screw spindles suspended from the 25 bridge, nuts attached to the said frame and screwed onto the said spindles and means for turning the vertical screw spindles so as to raise and lower the said frame.
- 30 4. In a machine for sluicing rail-tracks having a plurality of rails, a bridge, two bogie carriages, one at each end of the bridge, adapted to be supported by certain of the said rails, means at the middle part 35 of the said bridge for raising and lowering the said certain rails, means for moving the rails laterally with respect to the said bridge, means at the ends of the said bridge adapted to raise the said bogie carriages 40 from the said certain rails, rail pieces pointing in a direction at right angles to the said rails of the rail tracks, and means supporting and shifting the bridge on the said rail pieces.
- 45 5. In a machine for sluicing rail-tracks having a plurality of rails, a bridge, two bogie carriages, one at each end of the bridge, adapted to be supported by certain of the said rails, means at the middle part 50 of the said bridge for raising and lowering the said certain rails, means for moving the rails laterally with respect to the said bridge, means at the ends of the said bridge adapted to raise the said bogie carriages 55 from the said certain rails, supporting rollers at the ends of the said bridge, rail pieces above the said rails adapted to be placed in a parallel or transverse direction with respect to these rails, means for securing the 60 said rail pieces in either direction, and means for placing the said supporting rollers upon the said rail pieces.
6. In a machine for sluicing rail-tracks, a rail-track having a plurality of rails, a bridge, two bogie carriages, one at each end of the bridge adapted to be supported by certain of the said rails, sleepers for the rails, sets of rollers at the middle part of the said bridge adapted to raise and lower the said rails together with the said sleepers, 65 means for laterally moving the said rollers with the rails and sleepers, a second rail-track having a plurality of rails and sleepers, these sleepers being independent of the sleepers of the first rail-track, second sets of 70 rollers at the side of the middle part of the bridge adapted to embrace one rail of the said second rail-track, means for raising and lowering the said second set of rollers, means for laterally shifting the second sets 75 of rollers, means on the bridge supporting these second sets of rollers.
7. In a machine for sluicing rail-tracks, a rail-track, a bridge, two bogie carriages, one at each end of the bridge, rails in said rail-track supporting the said bogie carriages, sleepers for the said rails, a block at each side of the said supporting rails, a set of roller axes attached to each block and pointing in a downward direction, a roller on 80 each axis, pivots at the ends of the said blocks, the blocks being arranged to swing on said pivots, nuts attached to said blocks, a screw spindle with right and left hand threads screwed into said nuts, means for 85 turning the said spindle so as to move the sets of rollers toward and away from the said rails, a flange at the bottom end of each roller adapted to embrace the rails when the rollers are moved up against the rails, 90 a transversely movable support supporting the said blocks, a second rail-track having a plurality of rails, sleepers for the said second rail-track, these sleepers being independent of the sleepers of the first rail-track, 95 a block at either side of one rail of the second rail-track, a set of roller axes attached to either of the said second blocks and pointing in a downward direction, a roller on each axis, pivots at the ends of the second blocks, 100 the said second blocks being arranged to swing on said pivots, nuts attached to the second blocks, a screw spindle with a right and a left hand thread screwed into said nuts, means for turning the said spindle so 105 as to move the rollers toward and away from the said rail, a flange at the bottom end of each roller adapted to embrace the said rail when the rollers are moved up against the same, a supporting frame for 110 the pivots of the said second blocks, a connection between the said supporting frame and the said transversely movable support, means for varying the distance between the said supporting frame and the said transversely movable support, means for 115 moving the said movable support, the supporting frame, their attached rollers, the 120 125

6
rails and sleepers transversely with respect to said bridge, a frame suspended from the bridge and holding the said movable support, means for raising and lowering the said holding frame, a direct connection between the said supporting frame and the bridge, and means for raising and lowering the said supporting frame and the said parts attached to it.

In testimony that we claim the foregoing 10 as our invention we have signed our names in presence of two subscribing witnesses.

WILHELM ULRICH ARBENZ.
OTTO KAMMERER.
